(57) **CLAIM**

The ornamental design for a light having a bendable neck, substantially as shown and described.

DESCRIPTION

FIG. 1 is a perspective view of an example embodiment of an ornamental design for a light having a bendable neck between a light-producing end and a housing, in which the bendable neck is illustrated as being bent into a "U" shape; FIG. 2 is a side view of the example embodiment of an ornamental design for a light having a bendable neck shown in FIG. 1;

FIG. 3 is an end view of the light producing end of the example embodiment of an ornamental design for a light having a bendable neck shown in FIGS. 1 and 2, in which the bendable neck is bent to place the housing in view; FIG. 4 is an end view of the housing of the example embodiment of an ornamental design for a light having a bendable neck shown in FIGS. 1, 2 and 3, in which the bendable neck is bent to place the light producing end in view; and,

FIG. 5 is a side view of an example embodiment of an ornamental design for a light having a bendable neck, in which the bendable neck is illustrated as being bent into a loop, and having end views substantially as shown in FIGS. 3 and 4.

Broken lines in the illustrations of the FIGURES of the drawing indicate parts of the article that are not part of the design illustrated therein. For example, the bendable neck of the light may be longer or shorter than illustrated.
